LAMP SHADE

Jhi Hung Leung, Kowloon, Hong Kong, assignor to Star
Industrial Co., Ltd., Kowloon, Hong Kong

Filed Oct. 23, 1974, Ser. No. 517,440

Claims priority, application Great Britain Aug. 5, 1974

Term of patent 7 years

Int. Cl. D26—05

U.S. Cl. D48—16 D

FIG. 1

FIG. 2

FIG. 3

FIG. 1 is a perspective view of the lamp shade showing my new design;

FIG. 2 is a central vertical section thereof; and

FIG. 3 is a horizontal section taken on the line 3—3 in FIG. 2.

The panels radiating from the cylinder are transparent. Structure normally visible through individual panels has been omitted for convenience of illustration.

I claim:

The ornamental design for a lamp shade, substantially as shown and described.
